CLAIM

We claim the ornamental design for a cooking accessory, as shown and described.

DESCRIPTION

FIG. 1 is an isometric view, from the front top right, of a first embodiment of the cooking accessory in an open configuration.

FIG. 2 is an isometric view, from the back bottom left, of the first embodiment of the cooking accessory in the open configuration.

FIG. 3 is a plan view from the top of the first embodiment of the cooking accessory in the open configuration.

FIG. 4 is a plan view from the bottom of the first embodiment of the cooking accessory in the open configuration.

FIG. 5 is an elevation view from the front of the first embodiment of the cooking accessory in the open configuration.

FIG. 6 is an elevation view from the back of the first embodiment of the cooking accessory in the open configuration.

FIG. 7 is an elevation view from the right of the first embodiment of the cooking accessory in the open configuration.

FIG. 8 is an elevation view from the left of the first embodiment of the cooking accessory in the open configuration.

FIG. 9 is an isometric view, from the back bottom left, of a second embodiment of a cooking accessory in a closed configuration, wherein the second embodiment of the cooking accessory includes a Probe and an exploded-out IR sensor.

FIG. 10 is an isometric view, from the front top right, of the second embodiment of the cooking accessory in the closed configuration.

FIG. 11 is a plan view from the top of the second embodiment of the cooking accessory in the closed configuration.

FIG. 12 is a plan view from the bottom of the second embodiment of the cooking accessory in the closed configuration.

FIG. 13 is an elevation view from the front of the second embodiment of the cooking accessory in the closed configuration.

FIG. 14 is an elevation view from the back of the second embodiment of the cooking accessory in the closed configuration.

FIG. 15 is an elevation view from the right of the second embodiment of the cooking accessory in the closed configuration; and,

(Continued)

FIG. 16 is an elevation view from the left of the second embodiment of the cooking accessory in the closed configuration.
